UNITED STATES PATENT OFFICE.

HARVEY D. GEYER, OF DAYTON, OHIO, ASSIGNOR, BY MESNE ASSIGNMENTS, TO THE INLAND MANUFACTURING COMPANY, OF DAYTON, OHIO, A CORPORATION OF DELAWARE.

HANDWHEEL AND METHOD OF MAKING THE SAME.

Application filed August 30, 1922. Serial No. 585,189.

To all whom it may concern:

Be it known that I, HARVEY D. GEYER, a citizen of the United States of America, residing at Dayton, county of Montgomery, 5 and State of Ohio, have invented certain new and useful Improvements in Hand-wheels and Methods of Making the Same, of which the following is a full, clear, and exact description.

10 This invention relates to handwheels and includes such as those ordinarily employed as steering wheels for motor vehicles and the like.

15 An object of this invention is to provide an improved steering wheel having the arms of the spider rigidly secured to the central hub in an efficient and economical manner to give good appearance and high strength.

20 An object is to provide an improved method of assembling the wheel by inserting the spokes separately and later attaching the spokes to the central hub.

25 Further objects and advantages of the present invention will be apparent from the following description, reference being had to the accompanying drawings, wherein preferred forms of embodiment of the present invention are clearly shown.

30 In the drawings:

Fig. 1 is a plan view of one embodiment of the invention.

Fig. 2 is an elevation of the handwheel of Fig. 1.

Fig. 3 is a section on line 3—3 of Fig. 2.

35 Fig. 4 is a plan view of a modified form of the invention.

Fig. 5 is an elevation of the wheel of Fig. 4.

40 Fig. 6 is a section on line 6—6 of Fig. 5.

Fig. 7 is a perspective view of one of the stub arms of the metallic hub.

In the drawings, like or similar reference characters refer to like or similar parts throughout the several views.

45 In Fig. 1, numeral 10 designates the rim of the handwheel therein shown, and 11 the spider in its entirety. The construction of the spider 11 will now be described in detail. The central metallic hub comprises an upper part 15 and a lower part 16, the planes of division between these two parts preferably bisecting the stub arms 13 of the hub as clearly illustrated in Fig. 2. These parts 15 and 16 comprising the hub are

preferably die castings of aluminum or any 55 other suitable metal. The stub arms 13 of the hub are provided with recesses 14 to receive the inner ends 20 of the wooden spider spokes 12 which are so shaped as to snugly fit said recesses 14 while the hub parts 15 and 16 are tightly fastened together by bolts, screws or other suitable means. In Figs. 1 and 2, I have shown the spoke ends 20 as dovetailed both in plan view and in elevation and therefore when the hub parts 60 15 and 16 have been rigidly secured together this dovetail joint will positively prevent the spokes being withdrawn from the hub and makes a stronger joint. If desired however, the ends 20 may be dovetailed only 65 along one face or two faces instead of four as shown. Or the dovetail joint may be dispensed with entirely and the spoke ends 20 held in the recesses 14 by being clamped tightly therein. The screws 21 by which the hub parts 15 and 16 are secured together 70 preferably pass through the spoke ends 20 also, as clearly shown in the drawings.

The above described spider 11 may be first 75 completely assembled and then inserted in the rim 10 by any of the well known methods, such as by cutting recesses in the under side of the rim and then plugging up these recesses after the spider arms have been 80 inserted therein, or by sawing the rim in 85 halves, cutting recesses in one of the sawed faces for receiving the spider arms, and then securing the two halves of the rim together by glue or otherwise.

An important feature of this invention 90 however is the method by which the spider spokes may be separately inserted in radial or substantially radial recesses in the rim and then the spider spokes rigidly secured to the central hub. For this method of insertion the recesses 25 may be cut in the inner periphery of the rim 10 by a rotating cutter or routing wheel or by any other suitable means. The outer ends of the spokes 12 are then firmly pressed in place 95 in these recesses. In order to attach the free inner ends 20 of the spokes to the hub, the wheel is preferably turned upside down and the ends 20 first inserted in the recesses 100 provided therefor in the top hub portion 15. The lower hub portion 16 is then placed in position and the screws 21 inserted, thus 105 clamping the spoke ends 20 tightly between

the two hub portions. Preferably the hub portions 15 and 16 come tightly together to render the line of division between them as nearly as possible invisible.

- 5 6 In the modification shown in Figs. 4 to 7 inclusive, the spokes 12' are inserted in the recesses 25 in the rim 10 in the manner described above. The hub 30 however is made in only one piece and has its recesses 31
10 open at the bottom to permit the insertion of the inner ends 32 of the spokes 12', as clearly shown in Figs. 5, 6 and 7. The spoke ends 32 may be dovetailed as shown in Fig. 4, or not as desired. Preferably
15 these ends 32 are slightly wedge shaped, as best shown in Fig. 6, in order to insure a snug fit against the lateral walls of the recesses 31. The spokes are held firmly fixed in the recesses 31 by screws 33, preferably
20 two or more being used in order to insure a rigid connection.

While the forms of mechanism herein shown and described constitute preferred forms of embodiment of the present invention, it is to be understood that other forms might be adopted, all coming within the scope of the claims which follow.

What I claim is as follows:

1. A handwheel having a rim, dished
20 wooden spokes having greater width than thickness, and a metallic center having stub

arms having recesses for receiving the inner ends of the wooden spokes, said metallic center being divided into two parts the plane of division extending through said recesses to permit the lateral insertion of the spokes therein, and means interconnecting the upper and lower portions of the stub arms and passing through the inner ends of the spokes for clamping the spokes and the 40 divided hub portions rigidly together.

2. A handwheel having a rim, wooden spokes and metallic hub, recesses in said hub for receiving the spokes, the hub being split through the recesses to permit the insertion of the spokes in said recesses, and screws passing upwardly from below but concealed from above for holding the hub parts together.

3. A handwheel having a rim, wooden 50 spokes and metallic hub, said hub having recesses for receiving the inner ends of the spokes, the hub being divided through the recesses into upper and lower sections to permit the insertion of the spokes in the recesses and means passing through the spoke ends from one hub section to the other for retaining the hub sections and spokes rigidly in place.

In testimony whereof I hereto affix my 60 signature:

HARVEY D. GEYER.
